CLINCH-NUT MACHINE

Plummer E. Double, Detroit, and Frank Wascher,
Flint, Mich.

Application July 28, 1937, Serial No. 156,184

13 Claims. (Cl. 218—2)

This invention relates to machines for attaching clinch-nuts to other elements, and has particular reference to a machine for automatically attaching clinch-nuts such as disclosed in co-pending application, S. N. 81,887, filed May 26, 1936.

An object of the invention is the provision of a machine of the character referred to, which will overcome many of the difficulties inherent in devices of this kind heretofore known.

Another object of the invention is the provision of a device of the character referred to, which is simple in construction, efficient in operation, and easily adjustable to take care of a great variety of production problems.

Another object of the invention is the provision of a machine of the character referred to, with which clinch-nuts may be firmly attached to metals of several gauges without the necessity of manual adjustment.

Another object of the invention is the provision of a device of the character referred to, which will permit clinch-nuts to be attached to other elements in positions closer to bends and angles in those elements.

Another object is the provision of a clinch-nut attaching machine which has a higher degree of safety for the operator than machines heretofore known.

Another object is the provision of a machine of the character referred to, which is provided with a constant speed hopper which is adapted to feed nuts to the anvil in such manner as to obviate the possibility of clogging or jamming the machine.

Another object is the provision of a device of the character referred to, which is provided with a resiliently mounted anvil adapted to take up any overload on the anvil during its operation.

A further object is the provision of a device in which a complete riveting operation is accomplished by one revolution of the machine.

The foregoing and other objects and advantages of the invention will appear as the description proceeds, reference being made from time to time to the accompanying drawings, constituting a part of this disclosure, in which drawings like reference characters indicate like parts throughout, in which drawings:

Fig. 1 is a front elevation of the clinch-nut machine embodying our invention.

Fig. 2 is a side elevation of the machine illustrated in Fig. 1.

Fig. 3 is a perspective view of a clinch-nut such as used in connection with our machine.

Fig. 4 is a perspective view of a fragmentary piece of metal provided with an aperture, and to which the nut illustrated in Fig. 3 is to be attached.

Fig. 5 is a perspective view of the same piece of metal illustrated in Fig. 4, showing how the nut illustrated in Fig. 3, is inserted through the aperture, and before being attached by the machine.

Fig. 6 is an enlarged fragmentary detail, partly in section, illustrating the punch.

Fig. 7 is a section taken on line 7—7 of Fig. 8, and illustrates the sheet of metal and nut after attaching.

Fig. 8 is a plan view of the piece of metal after the nut has been attached thereto.

Fig. 9 is a side elevation of the machine and illustrates a section taken on line 9—9 of Fig. 1.

Fig. 10 is a horizontal section taken on the line 10—10 of Fig. 2.

Fig. 11 is a rear elevation, with parts broken away and partly in section, taken on line 11—11 of Fig. 10.

Fig. 12 is a section taken on line 12—12 of Fig. 10.

Fig. 13 is an enlarged fragmentary section taken on the line 13—13 of Fig. 12.

Fig. 14 is a section taken on the line 14—14 of Figs. 9 and 16.

Fig. 15 is a section taken on line 15—15 of Fig. 9.

Fig. 16 is an enlarged fragmentary front view with parts broken away and with the anvil, partly in section, taken on line 16 of Fig. 14.

Fig. 17 is a fragmentary plan view, partly in section, illustrating the tucker bar, raceway, and anvil.

Fig. 18 is a view, partly in section, taken on line 18—18 of Fig. 17, illustrating the raceway from the hopper leading into the nut carrier bar.

Fig. 19 is a fragmentary view, partly in section, taken on the line 19—19 of Fig. 17 and illustrates the position of the tucker bar when ready to place a nut onto the anvil.

Fig. 20 is an elevation, partly in section, illustrating the anvil and nut carrier bar assembly, and illustrating, by dotted lines, several positions assumed by the tucker arm, tucker, and nut carrier bar.

Referring now more particularly to the drawings, it will be seen that in the embodiment herein disclosed, the principal working parts of our invention are housed within a casting 35, the latter being secured to a second casting 36 by 55

means of fillister head screws 37. The casting 38 is annular in form and is arranged to telescope the tubular member 38, the upper end of which is adapted to engage a shoulder 39, formed on the casting 36 to provide a bearing surface. At the lower extremity the tubular member 38 telescopes a three-footed base member 40, the latter being split on one side as at 41, and provided with fillister head screws 42 adapted to draw the split section together. The pedestal assembly just described enables the operator to adjust the machine to various heights.

Adjustably mounted on the tubular member 38 is a motor supporting bracket 43 which is also split on one side and provided with cap screws 44, to enable it to be secured in any desired position on the tubular member 38. A cover plate 45 (Fig. 2) is adapted to form a cover for the opening in the side of the casting 35, and its removal permits ready access to the working parts contained within the casting 35, as is described more particularly hereinafter.

Superimposed on the housing 35 and secured thereto by means of bolts 46, is a bracket 47 which is adapted to support the hopper 48 as hereinafter described.

Tie bolts 49 extend vertically through the casting 35 for purposes of reinforcement. These tie bolts 49 carry nuts 50 at each end, the nuts at the top being arranged to engage offsets 51 formed on the exterior of the casting 35, and the nuts at the bottom being arranged to engage bosses 52 formed inside at the bottom of the casting 35. The front of the casting 35 is provided with a recess 53 which is arranged to provide necessary clearance for stock to be passed over the anvil 54, the latter being supported by the front end of the anvil relief lever 55, as hereafter described. The lever 55 is fulcrumed on a pin 56 which is supported at either end in the sides of the casting 35. The rear end of the anvil relief lever 55 (Fig. 9) terminates in a yoke 57 through which is extended a pin 58, which may be held against displacement by any suitable means such as by cotter pins. An eye bolt 59 is arranged to engage the pin 58 and to extend downwardly through an internally threaded boss 60 formed in the bottom of the casting 35. An externally threaded screw 61 is threaded into the boss 60, and is adapted to put tension on the spring 62, which is carried by the eye bolt 59. The spring 61 is held against downward displacement by means of washer 63, and a castellated nut 64. By properly adjusting the tension on the spring 62, any overload on the anvil 54 will be automatically compensated for as explained more fully hereinafter.

The anvil 54 (Fig. 20) is provided with a bayonet 65 which is adapted to slide vertically in a bayonet slot 66 formed in the member 67, which is preferably a steel casting secured to the front end of the main casting 35 by means of fillister head screws 68. The anvil 54 rests of its own weight on the front end of the anvil relief lever 55 and is secured against upward displacement by means of a locking pin 69 which is adapted to engage a slot 70 formed in the back of the anvil 54, and a counter bored hole 71 in the steel casting 67. The locking pin 69 has a centrally disposed bore which is arranged to carry a compression spring 72 which normally holds the pin 69 in position of engagement with the anvil 54 as shown in Fig. 20. The anvil is provided with a horizontal passageway 73 immediately in front of the locking pin 69, into

which a tool may be inserted to force the locking pin 69 out of engagement with the anvil 54. When the locking pin 69 is pushed out of engagement with the anvil 54, the latter may be slid upwardly and removed from the bayonet slot. This is an important feature as it enables the operator to remove the anvil with great speed and rapidity. The anvil 54 (Fig. 20) is provided on one side with a fixed jaw 74 (Fig. 16), which is secured thereto by means of rivets 75, and on the other side with a movable jaw 76 which in turn is provided with a centrally positioned lug 76a, through which passes pivot pin 77, the latter being press-fitted into a bore provided therefor in the anvil.

A compression spring 78 is carried in a recess formed in the anvil below the pivot pin 77, and is adapted to rock the jaw 76 on the pivot 77, and force the upper end of the jaw 76 toward the fixed jaw 74 in order that a clinch-nut may be firmly gripped between said jaws.

Supported at each end, by means of bearings 80 (Fig. 9), positioned in suitable recesses at either end of the casting 35, is a main drive shaft 81 which is lubricated in the bearings 80 by suitable oil cups 83. At the front end of the shaft 81, there is machined an eccentric crank 84 to which is mounted for reciprocal motion, a plunger link 85, which is provided with a suitable bearing 85a and oiling means 85b. To the lower end of the plunger link 85 is movably attached, by means of pin 86, a plunger 87 which is provided with suitable bearings 88 and 89, the latter being part of the cover plate 92. To the lower end of the plunger 87 is threadingly supported the punch 90. The lower portion of the plunger 87 is split, and the split section is provided with a threaded horizontal bore which is adapted to receive a locking screw 91, the latter being adapted to secure the punch 90 to be advanced or retreated to any desired position, and enables the punch 90 to be easily removed in the event that a replacement is necessary. Positioned about the punch 90 is a stripper spring 91 which holds the work in alignment on the anvil 54 during the clinching operation, and automatically releases the work from the punch 90 after the clinching operation. The eccentric crank 84, the plunger link 85 and the plunger 87 are covered by means of the cover plate 92 which is secured to the casting 35 by screws 93.

Keyed to the shaft 81 is a cam member 94 (Fig. 9) which is arranged to engage a roller 95 carried on the tucker arm 96, the latter being formed at its upper end with a yoke member 97 (Fig. 15) which is pivoted on the shaft 98, the latter being secured at either end in bosses 99 formed in either side of the main casting 35. The spacer 94b is positioned on the shaft 81 and is arranged to contact a thrust washer 94c also carried on shaft 81, and in contact with the shoulder formed on the inside of the casting 35. The spacer 94b and the thrust washer 94c are intended to maintain the cam 94 in predetermined position on the shaft 81.

Mounted on the shaft 98 intermediate the arms of the yoke 97 is a second yoke 100, the arms of which are downwardly disposed and adapted to engage opposite sides of the main shaft 81, for the purpose of centering the tucker arm 96 immediately below the main shaft 81. At the lower end of the tucker arm 96 is a roller 101 which is arranged to engage a cam surface 102 formed on the under side of the nut carrier bar 103, the latter being pivoted at its rear end on a pin 75.

104 carried in a bracket 105. The bracket 105 (Fig. 11) is adjustably secured to the outside of the housing 35 by means of cap screws 106. Upon loosening the cap screws 106, the bracket may 5 be lowered or elevated by the adjusting screw 107, and locked in position by means of nut 108. The front end of the nut carrying bar 103 remains free for upward and downward movement under the influence of the cam surface 102 riding on the 10 roller 101.

The arm 96 is moved forward and backward by reason of the engagement of the roller 95 with the cam surface 94a on the member 94. The tucker arm 96 is urged forward by means of a 15 tension spring 109, which is secured at one end to the tucker arm 96, and at the other end to a pin 110 extending through the front of the casting 35. The bar 103 is provided in its upper surface with a T-slot 111 in which is adapted to 20 reciprocate a tucker member 112, the latter being provided at its rear end with a yoke 113 which is arranged to engage a pin 114 carried by the arm 96. Formed in the upper surface of the bar 103, ahead of the tucker 112, is a second slot in 25 which is secured, by means of fillister head screws 115, a steel insert 116 (Figs. 18 and 19) in which is formed a T-shaped slot 117, which is of sufficient size to accommodate clinch nuts 118 such as disclosed in Fig. 3. The clinch nuts 118 carried in the insert 116 are arranged to be moved 30 toward the anvil 54 by means of the forward movement of the tucker 112 as will be explained more fully hereinafter.

The insert 16 (Figs. 18 and 19) is provided 35 with an opening 119 on one side to permit the introduction of clinch nuts thereto from the raceway 120, which extends from the hopper 48. Secured by means of a rivet 121 to one side of the bar 103 immediately below the opening 119 in the 40 insert 116, is a cam 121. This cam extends upwardly along the side of the insert 116 and is intended to push the nuts back in the raceway 120 upon the upward movement of the bar 103. Secured to the steel insert 116 by means of screws 45 122 is an L-shaped cover member 123. This member 123 is positioned on the insert 116 immediately above the opening 119 therein. The cover member 123 is provided on its under side with a flat spring 124 which is secured thereto by means of rivets 125. The spring 124 is intended to exert pressure on the nut 126 immediately ahead of the nut 118 (Fig. 17) so that, when the nut 118 is advanced to the position of nut 126 and toward the anvil by the tucker bar 112, there 50 remains an opening in the insert 116 for the reception of another nut from the raceway 120 on the downward movement of the bar 103. An adjusting screw 128 (Fig. 20) is mounted in a boss formed in the steel casting 67, and is adapted 55 to limit the downward movement of the free end of the bar 103 so that exact alignment may be had between the opening 119 in the insert 116 and the raceway 120. The set screw 128 is formed with a cone shaped end. The under edge of the bar 103 is provided with a groove 103a which is adapted to contact the cone in such manner that when the screw 128 is moved inwardly the bar 103 is held in a higher position and when the screw is moved outwardly the bar is allowed to 60 assume a lower position. A slight turn of the screw 128 effects the usual required adjustment. A tension spring 129 is secured to the under side of the bar 103 and its other end is connected to the anvil relief bar 55 and is intended to steady 65

the bar 103 and prevent vibration thereof on the roller 101.

The shaft 81 is driven by means of an electric motor 130 through the clutch 131, the fly wheel 132, the belt 13, the idler pulley 134 and the belt 135. The motor 130 is mounted by any suitable means on the bracket 43. The idler pulley 134 is mounted on the stud 136 which is secured by means of a nut to the casting 35. The idler pulley 134 is provided with a suitable bearing 137 which is lubricated by means of the oil cup 138. The clutch 131 consists of a plate 139 which is freely mounted on the shaft 81 and is secured by means of fillister head screws 140 to the fly wheel 132, the latter being provided with a bearing 132a and 15 secured on the shaft 81 by means of thrust collar 132b held by suitable set screws. The clutch plate 139 is arranged to engage the clutch collar 141 which is connected to the shaft 81 as at 142 by means of clutch pin 143, which is slidably mounted in a recess formed in the clutch collar 141. The pin 143 is normally held in extended position by means of compression spring 144 which is carried in an internal bore provided in one end of the clutch pin 143. The spring 144 20 is arranged to contact the thrust collar 146 which is secured to the clutch collar 141 by means of rivets. The clutch pin 143 is held against rotation by means of a key which is arranged to engage a slot formed in the clutch pin 143. The 25 working surface of the clutch pin 143 is adapted to engage corresponding working surfaces 151 formed on the inside of the clutch plate 139. The clutch pin 143 is held in inoperative by means of the clutch release bar 152, the upper end of 30 which is arranged to engage a slot formed in the under side of the clutch pin 143. The clutch release bar is slidably mounted in recesses formed in the main housing 35 and secured against displacement by cover plates 153 and 154 which are 35 secured in position by cap screws 155. The clutch release lever 152 is normally held in upward position by means of a compression spring 156, which rests at the bottom on the casting 35, and at the other end abuts the end of a bore 157 40 formed in the lever 152. The clutch release bar 152 is provided along one side with an under cut bearing surface 158 which is arranged to engage the trip pawl 159 rockingly secured by means of stud 160 to the trip lever 161, the latter being 45 pivoted by means of stud 162 in a boss 163 formed on the inside of the casting 35. The pawl 159 is arranged to rock downwardly and is held against upward displacement by means of an offset, which is arranged to ride on the top surface 50 of the lever 161. A tension spring 165 is secured between a mounting stud, fastened in the upper side of the pawl 159, and a mounting stud 167 which is carried in the upper surface of the trip lever 161. This spring is arranged to return the 55 pawl 159 to its normal position after it has been rocked downwardly, as will appear more fully hereinafter.

A cam block 168 is slidably mounted in the casting 35 and secured against displacement by 60 the cover plate 153, and rests of its own weight on the top of the trip lever 161. The cam block 168 is formed at its upper end with a curved surface 169 which is adapted to ride on cam surface 170, formed on the clutch collar 141, for the 65 purpose of holding the pawl 159 out of engagement with the lever 152, so that the latter may return to its normal position to enable it to engage the slot formed in the clutch pin 143, to 70 disengage the clutch pin 143 from the clutch plate 75

138, upon the completion of a single revolution. With this mechanism the clutch can remain in engaged condition only during one revolution of the fly wheel.

5 The trip lever 161 is connected to a foot pedal 171 by means of a connecting rod 172 so that the clutch may be engaged for one revolution only by the downward movement of the foot pedal 171. In order to re-engage the clutch 138 after one 10 revolution it is always necessary to release the foot pedal 171.

The hopper 48 is supported by means of a spider 173 which is mounted for rotation on stud 174, which in turn is secured to the hopper base 15 175, the latter being secured to the bracket 47 by means of cap screws 176. The stud 174 is provided with threads at either end and arranged to engage nuts 177. The hopper 48 is rotated on the stud 174 by means of a belt 180, which passes 20 around it, and the pulley 181 the latter being driven by the motor 183. The motor 183 and pulley 181 are supported by a bracket 184 which is secured to the bottom of the hopper base 175. A steel plate 191 is secured to the base 175. The 25 plate 191 covers a groove 191a formed in the base 175. The groove 191a communicates with the raceway 120 and serves as part of the track for nuts fed from the hopper 48.

After the machine is fully assembled as hereinabove described and connected to a proper source of electrical power and a sufficient quantity of clinch nuts is placed in the hopper 48, a typical operative cycle is described as follows:

The nuts travel downwardly in the raceway 120 35 to a position adjacent the nut carrier bar 103. When this bar is in its lowered position as shown in Fig. 18, the opening 119 in the insert 116 is then in alignment with the raceway 120 so that a nut, designated in this instance 118, may 40 enter the steel insert 116. When the bar 103 is in the position shown in Figs. 9 and 18, the machine is in neutral position. If the operator then depresses the foot pedal 171, the trip lever 161 is actuated, causing the clutch release bar 45 152 to be lowered, disengaging the same from the clutch pin 143, so that the latter may be moved into engagement with the clutch plate 138, which is secured to the flywheel. Upon engagement of the clutch, the shaft 81 is caused 50 to rotate, rotating with it the cam 94 and the eccentric crank 84. As the cam 94 rotates it permits a forward movement of the tucker arm 96 under the influence of the spring 109, and as the tucker arm 96 moves forward, the roller on the end thereof, which is in contact with the cam surface 102, causes the nut carrier bar 103 to be 55 elevated to the position shown in Fig. 19, and shown by the dotted lines in Fig. 20. After the nut carrier bar 103 has reached the limit of its upward movement, the tucker arm 96 continues to move forward until the tucker bar 112, which is actuated thereby, strikes the nut which 60 has just been introduced from the raceway 120 moving it forward a sufficient distance to permit the entrance of another nut from the raceway 120. The pedal 171 must be depressed a sufficient 65 number of times to permit a sufficient number of nuts to enter the nut carrier bar 103 before a nut will be introduced to the anvil. When the nut 70 carrier bar is completely filled with nuts, the next operation of the machine will be effective to introduce a nut to the jaws of the anvil 54. An element, such as a sheet of metal with an aperture such as disclosed in Fig. 4, is then positioned 75 on the anvil so that the exposed portion of the

nut is extended through the aperture as illustrated in Fig. 5. In this condition the machine is now ready to be actuated for an effective clinching operation. When the foot pedal 171 is depressed this time causing the shaft 81 to rotate, the punch 90 is moved downwardly to contact the nut then in position on the anvil 54. The spring 91a tends to hold the sheet of metal in fixed relation until the punch 90 has clinched the upper surface of the nut as illustrated in Fig. 6. As the punch 90 is withdrawn from the anvil 54, the spring 91a causes the nut, which is then attached to the metal, to become disengaged from the punch 90.

The operation of the punch 90 is so timed that its working stroke is completed and it has entered its upward movement before the nut carrier bar 103 is elevated. In other words, the upward movement of the nut carrier bar 103 is timed so that it follows the punch 90 in its upward travel. This is an important feature of the invention as three separate and distinct operations are performed with one throw of the bar 103. The operations performed are as follows: First, the bar 103 in moving upwardly contacts the under side of the sheet of metal, or other element to which a nut has been clinched by the punch 90, dislodging the same from the anvil 54; second, when the insert on the bar 103 is in alignment with the anvil jaws, a nut is injected into the anvil leaving a space in the insert opposite the raceway 120; third, the space just referred to is then filled by the introduction of a new nut from the raceway 120.

As hereinbefore described, this machine makes a complete cycle upon one revolution of the shaft and each successive cycle or clinching operation requires the operation of the foot pedal 171. Should the anvil 54 become overloaded for any reason, because too thick a piece of metal is being used or because the metal is misplaced on the anvil, the overload will automatically be taken up and the shock absorbed by means of the spring 62. This is an important feature of the invention as it obviates much difficulty heretofore encountered in clinching machines. Another important feature of this invention is that because of the construction and arrangement of the hopper, the nuts in the raceway 120 are at all times free to travel up and down in said raceway. Because the nuts are deposited in the raceway 120 in an opposite direction to the rotation of the hopper, there is no opportunity for the nuts to become jammed. The cam 121 positioned on the side of the bar 103 imparts a backward and upward motion to all the nuts in the raceway 120 as the bar moves upwardly. This gives the nuts a fresh start downwardly when the bar 103 is returned to its lower position thereby enabling a new nut to be introduced to the insert 116 by force of gravity.

Having described our invention, what we claim and desire to secure by Letters Patent is:

1. In a clinch-nut machine, including a housing, the combination of an anvil mounted on said housing, a drive shaft, means for intermittently revolving said shaft, a punch mounted on said drive shaft, a nut carrier bar adapted to guide nuts to said anvil, and means actuated by said shaft for raising and lowering said nut carrier bar and advancing toward said anvil nuts carried by said bar.

2. In a clinch-nut machine, including a housing, the combination of an anvil, a drive shaft, means for intermittently connecting said shaft

to a power source, a punch mounted on said shaft, a nut carrier bar adapted to receive nuts and having means for discharging nuts, and means actuated by said drive shaft for raising and lowering said bar and actuating said discharging means.

3. In a clinch-nut machine, including a housing, the combination of an anvil mounted to said housing, a drive shaft intermittently connectible to a power source, a punch adjustably mounted for reciprocation by said shaft, a nut carrier bar, means carried by said bar for receiving and discharging nuts, a cam on the under side of said bar, a tucker reciprocably mounted in said bar, said tucker being in alignment with the nuts received by said bar, means actuated by said shaft adapted to raise and lower said bar, and means connected with said shaft actuated means for actuating said tucker.

4. In a clinch-nut machine, including a housing, the combination of an anvil, a drive shaft, a punch mounted on said shaft, means for intermittently connecting said shaft to a source of power, a nut carrier bar adjustably pivoted at one end to said housing, a cam actuated by said shaft, an arm actuated by said cam, said arm having a roller at its lower end adapted to ride on a cam surface formed on the under side of said bar, means on said bar for receiving nuts from a source adjacent thereto, and a tucker slidably mounted on said bar in alignment with the nut receiving means, said tucker being arranged to be actuated by the aforesaid arc.

5. In a device of the character described, including an anvil and a raceway for supplying nuts, the combination of a drive shaft, a nut carrier bar pivoted at one end, the opposite end being adapted to be moved up and down, means between said shaft and said bar, said means being arranged to raise and lower said bar, means carried by said bar for receiving a nut from said raceway, when said bar is in its lowest position, and means actuated by said drive shaft for advancing a nut to said anvil when said bar is in its highest position.

6. A device as defined in claim 5, wherein the nut carrier bar is provided with a cam adjacent said raceway, which said cam is adapted to retain nuts in said raceway during the up and down movement of said carrier bar.

7. A combination as defined in claim 5, where-

in the free end of said nut carrier bar is arranged to travel adjacent one side of said anvil, whereby material worked upon is automatically dislodged from said anvil by the up stroke of said bar.

8. In a device of the character described, including an anvil and a nut supplying raceway, the combination of a nut carrier bar, one end of which is arranged to move up and down adjacent said anvil, means carried by said bar for successively receiving nuts from said raceway, a tucker for advancing the nuts on said bar, means for raising said bar, and means for advancing said tucker at the end of the up stroke of said bar.

9. The combination as defined in claim 8, wherein there is a resilient element carried by said bar to hold in predetermined position the nut adjacent said tucker, on the down stroke of said bar.

10. In a clinch-nut machine, including a housing, a punch, and means for driving said punch, the combination of a bearing member secured to said housing, a slot in said bearing member, an anvil having a member adapted to slide in said slot, a rocker arm for movably supporting said anvil, and retractable locking means for limiting the upward displacement of said anvil.

11. In a clinch nut machine, including a housing, and a nut feeding raceway, the combination of an anvil mounted on said housing, said anvil having jaws adapted to grasp a nut, a drive shaft, means for removing said shaft, a punch mounted on said drive shaft, a nut carrier bar, means on said bar for receiving a nut from the raceway, means actuated by said drive shaft for raising and lowering said nut carrier bar, and means actuated by said drive shaft for advancing a nut from said carrier bar to the jaws of said anvil.

12. The combination defined in claim 11, wherein the punch is arranged to move to and away from said anvil and the nut carrier bar is arranged to follow the punch on the up stroke.

13. A device as defined in claim 5, wherein the nut carrier bar is provided with a cam adjacent said raceway, which said cam is adapted to impart a retreating motion to nuts in said raceway upon the upstroke of said bar.
